(57) **CLAIM**

The ornamental design for a flying pest trap, as shown and described.

DESCRIPTION

This application is related to the United States Non-provisional utility application filed concurrently herewith under 37 CFR 1.53(b), having a title of Flying Pest Trap, identified 13/158,285 and filed under customer No. 35856, the entire contents of which are hereby incorporated by reference.

FIG. 1 is a perspective view of my new ornamental design for a flying pest trap;

FIG. 2 is a top plan view of the flying pest trap shown in FIG. 1; and,

FIG. 3 is a cross sectional view of the flying pest trap, shown along line 3-3 of FIG. 2.

One illustrative embodiment is provided. The illustrated embodiment shows the structure of a flying pest trap. The broken lines in the drawings are for illustrative purposes only and form no part of the claimed design.
